UNITED STATES PATENT OFFICE.

BESSIE C. PETERSON, OF CHICAGO, ILLINOIS.

DESIGN FOR A BEAUTY-BOX.

45,767.

Specification for Design.

Patented May 12, 1914.

Application filed February 7, 1914. Serial No. 817,355. Term of patent 14 years.

To all whom it may concern:

Be it known that I, BESSIE C. PETERSON, a citizen of the United States, residing at Chicago, in the county of Cook and State of Illinois, have invented a new, original, and ornamental Design for Beauty-Boxes, of which the following is a specification, reference being had to the accompanying drawing, forming part thereof.

The drawing is a perspective view of a beauty box made according to and illustrating my new design.

I claim:

The ornamental design for a beauty box, as shown.

BESSIE C. PETERSON.

Witnesses:

MARY C. NEWELL,
MARY C. DINNEEN.
